(57) CLAIM

The ornamental design for a window, as shown and described.

DESCRIPTION

FIG. 1 is a front perspective view of a window showing my new design.

FIG. 2 is a rear perspective view thereof.

FIG. 3 is front elevation view thereof.

FIG. 4 is rear elevation view thereof.

FIG. 5 is a side view thereof.

FIG. 6 is an opposite side view thereof.

FIG. 7 is a top view thereof.

FIG. 8 is a bottom view thereof.

FIG. 9 is a sectional view taken at line 9—9 of FIG. 4.

FIG. 10 is a sectional view taken at line 10—10 of FIG. 4.

FIG. 11 is a perspective sectional view taken at line 11—11 of FIG. 2.

FIG. 12 is a perspective sectional view taken at line 12—12 of FIG. 1.

FIG. 13 is a plan sectional view of one frame extrusion of the window, which extends along the lengths of the top and bottom moveable sections of the window frame and the two opposite vertical moveable sections of the window frame; and,

FIG. 14 is a plan sectional view of another frame extrusion of the window, which extends along the lengths of the top and bottom stationary sections of the window frame and the two opposite vertical stationary sections of the window frame.

The broken lines in the figures are for illustrative purposes only and form no part of the claimed design.
